PIPE TONGS

William H. Martin, Hebbronville, Tex.

Application October 14, 1940, Serial No. 361,094

3 Claims.

(CL 255—35)

The invention relates to an improvement in pipe tong and the general combination assembly and the manipulation thereof.

In running strings of pipe into and out of a well bore the pipe sections are threaded end to end in making up the string of pipe, and unthreaded in disconnecting the pipe.

In the rotary method of drilling, the drill stem is made up of heavy pipe sections which must be coupled firmly together, first, for the purpose of transmitting the torque applied to the drill stem to effect rotation of the drill bit, and second, to form a fluid-tight joint which will withstand the tremendous pressure applied to the drilling mud being circulated through the drill pipe. Great difficulty is encountered in making up the threaded connection tightly enough to perform the foregoing functions. The usual practice is to support that portion of the string of pipe which remains in the well bore by a set of slips in the rotary table, and in order to make the joint up at a convenient elevation to the drilling crew, the slips are usually positioned so as to catch the upstanding pipe end about three or four feet from the end so that this portion three or four feet long projects above the rotary table. One pipe tong is connected to this upstanding end and suitably anchored so as to hold it against rotation. Where a pipe string is being made up the new section of pipe is then inserted in this upstanding end and turned so as to make up the thread. A second pipe tong is connected to this upper section of pipe and a pull exerted on such second tong in order to make up the threads tightly. The practice is to use what is generally known as a jerk line whereby a mechanical pull is exerted upon this upper tong to jerk the tong and thus tighten the thread.

The practice has been to place these tongs on opposite sides of the pipe so that the anchor cable and the jerk line both exerted a pull in the same direction but on opposite sides of the pipe. The net result was to impart to the pipe a bending action where it projected above the slips. The pipe was thus bent first in one direction and then on the next trip into the well it might be bent in another direction with the result that the pipe metal was crystallized at the point of bending and result in defects or splitting of the pipe. A split thus created in the pipe permitted leakage and destruction of the pipe.

The present invention contemplates an assembly and a mode of operation of the tongs wherein this bending action will be avoided, and the stress

applied to the pipe would be a simple torque tending to make up the pipe.

The invention contemplates that the two pipe tongs will be so arranged with their handles in substantially the same vertical plane and the anchor cable and the jerk line so disposed and connected to the respective tongs that the pull on the jerk line will be opposed by an equal and opposite reaction on the anchor line so that the net result will be an elimination of the bending action or bending moment which has been heretofore applied to the pipe.

It is one of the objects of the present invention to position the jerk line so that the pull thereon is opposite to the anchor line when making up or breaking out pipe joints.

Another object of the invention is to suspend a pair of tongs in making up or breaking out pipe joints one over the other.

Another object of the invention is to provide a suspension mechanism for a pipe tong so that a second tong may be manipulated within the confines of said suspension mechanism.

Another object of the invention is to provide a pipe tong with side arms by which it may be suspended.

Another object of the invention is to maintain the pipe straight while making up the joint.

Another object of the invention is to provide an upstanding extension on a pipe tong to receive the suspending device.

Other and further objects of the invention will be readily apparent when the following description is considered in connection with the accompanying drawing, wherein:

Fig. 1 is a top plan view looking down on a special type of tong to be utilized in connection with the invention.

Fig. 2 is a side elevation of the make-up and break-out tongs as they are used in combination.

Fig. 3 is a top plan view diagrammatically illustrating the manner of practicing the invention.

In Fig. 3 the rotary mechanism is illustrated generally at 2, the hoisting equipment at 3, and the drill pipe being made up or broken out is seen at 4. The pipe 4 is in the form of an upstanding pipe end 5, as best seen in Fig. 2 wherein the pipe is supported in the rotary table 2 by means of a set of slips 6, which are arranged to wedge into the opening in the rotary table so as to support the weight of the string of pipe 4. The pipe sections may be constructed in any desired manner, such as flush joint, tool joint or

upset end pipe. That shown in Fig. 2 is known as upset flush joint pipe.

As pointed out heretofore, the prior practice has permitted the bending of this upstanding pipe end 5 at about the elevation 7 where the pipe enters the slips 6, and in the present invention it is intended that this bending of the pipe will be eliminated by the construction and arrangement of the tongs. The anchor tong is illustrated at 10 and is best seen in Fig. 1 where it comprises the jaws 11 and the handle 12. The handle is of peculiar construction in that it has the arms 13 and 14 extending from the opposite sides thereof adjacent the head or jaw 11. These arms may be of any desired length and have the openings 15 in the end thereof and are preferably made integral with the handle 12.

The end of the handle may have an opening 17 therein to receive the anchor line 18 by which the tong is held against rotation, as best seen in Fig. 3.

In order to suspend the tong in a horizontal plane as seen in Fig. 2, an extension 20 is shown as having been applied to the handle. In the drawing it is illustrated in the form of a rod affixed to the handle and projecting upwardly therefrom a short distance. With the ordinary size of tong in general use the extension 20 will approximate two feet in length. An opening 21 may be provided in the upper end of the extension. It is to be understood that this extension may be made integral with the tong by turning up the end of the handle, or it may be affixed as shown in the drawing.

The suspending mechanism is in the form of a link 22 connected in the opening 21 in the extension 20 and a turn buckle 25 connected in each of the openings 15 in each of the arms 13 and 14. The two turn buckles and the link 22 are in turn engaged in a ring 26 carried by the supporting line 27. In this manner the tong, by suitable adjustment of the turn buckle, may be suspended in a normally horizontal plane.

When the tong 10 is thus positioned about the pipe end 5 and anchored to the cable 15 it will hold the pipe 5 firmly in place.

The pipe end 30 is now moved into position and its threaded pin end inserted into the upstanding threaded box end of the pipe 5. The tong 32 is then connected about the pipe end 30 so that the jaws 33 firmly grip the pipe. The handles 34 extending from the jaws will be positioned over the handle 12 of tong 10 as best seen in Fig. 3.

The tong 32 is suspended by a link 35 and the turn buckles 36 where the turn buckles are connected by the loop 37 at the side of the handle, and the link 35 is attached by the loop 38 to the outer end of the handle. These two turn buckles 36 and the link 35 are all connected to the ring 39 and the suspension line 40 so that this tong 32 will also be suspended in horizontal position. It should be noted, however, that the link 22 and the turn buckles 25 on the tong 10 are substantially longer than those on the tong 32.

The end of the handle 34 has an opening 42 therein to which the jerk line 43 is connected. This line in turn passes over a cathead 44 which is arranged to be operated by a hoisting mechanism 3. When the tongs are positioned as shown in Fig. 3 with the handles 12 and 34 in substantially vertical alignment, it seems obvious that the pull exerted on the jerk line 43 will exert a torque on the pipe and that this torque will be transmitted to the tong 10 and the anchor line 18, and where the jerk line and the anchor line ex-

tend in opposite directions there will be a reaction through the tongs to the anchor line which will be equal and opposite to the pull on the jerk line. The arrangement of the anchor line and the jerk line so that they are oppositely extending eliminates any bending moment as applied to the pipe end 5 so that any stress applied to the pipe is a simple torque reaction.

One of the particular advantages of the present arrangement is that the tong 32 may be positioned inside of the suspending mechanism for the tong 10 and still permit its ready manipulation or operation. This is accomplished by the provision of the side arms 13 and 14 and the extension 20 so as to allow the turn buckles 25 and the link 22 to be spaced far enough apart and far enough above the tong 10 to accommodate the handle 34 of the tong 32 within the confines of such suspending mechanism.

It should be borne in mind that with the deep well higher temperatures are encountered in the bottom of the well bore. For instance, in a 10,000-ft. well a temperature of 240° or 250° F. can be expected. Such a temperature causes the metal of the drill stem of the tool joints to expand and this results in an expansion of the rotated portions. An expansion of this sort often permits leakage where the drill stem is subjected to the pressure of the drilling mud on the inside. Often the mud pressure exceeds 1,000 or 1,500 pounds per square inch. It is imperative, therefore, that the tool joint be made up as tightly as possible at the surface so that when this expansion occurs a tight joint will be maintained.

With the practices as outlined heretofore where an upstanding portion of the pipe above the rotary table was bent in making up the joint, it seems obvious that where one piece of pipe was bent away from the vertical and the other piece of pipe was suspended in a vertical position by the hoisting equipment, that it would be difficult, even impossible, to make the joint up tightly while the two threaded portions were thus misaligned. No amount of turning or torque applied to a joint could possibly make the joint up tightly when the pipes themselves were misaligned.

As compared to this, if the upstanding pipe end is maintained in a vertical position, then the joint can be made up tightly because the two pipe sections will be in alignment. As an illustration of this an old and muchly used string of drill pipe employed on a well recently drilled caused five washouts and destroyed five tool joints during the drilling of one well. This same string of pipe was then used on the next well and the tong of this invention used in making up the joints. In the drilling of this next well the same string of pipe was used to drill to a depth of 10,300 feet and no washouts occurred. Obviously this evidences the proof of the fact that even old and worn joints, when properly made up will not wash out.

Another feature of advantage with the present tong is that where there is no bending imparted to the pipe, the pipe will render a much longer service because it has been noted that where the end of the pipe is bent and then lowered into the well, when the pipe is rotated the end of each section is out of alignment and executes an eccentric motion in the well. This has been apparent from the fact that the tool joints very often show a great deal of wear on one side where the pipe bent sufficiently to cause the tool joint to rub on the side of the well bore. This bending crystallizes the molecules of the material in the pipe and results in crystallization and breakage.

In practicing the present invention it may be desirable to have extra tongs on the well of the usual type which may be used in breaking out the joints when the pipe is removed and the present tong used only in making up the joint going into the hole. Either practice may be followed as desired.

Broadly, the invention contemplates a method and apparatus for make-up and break-out pipe joints which will eliminate the bending of the pipe and provide a simple torque reaction.

What is claimed is:

1. A tong assembly to make and break the joints of a string of pipe suspended in a well bore without imparting a bending movement to the pipe above the point where it is supported which assembly includes a pair of pipe tongs disposed one above the other to grip the respective pipe ends of the joint, means to exert a pull on one tong, independent means to anchor the other tong against the pull on the first tong, and independent means to suspend said tongs in spaced relation one above the other in operative position so that one tong is within the confines of the suspending means of the other tong and the force of the pull is directly resisted by said anchor so as to avoid bending the pipe.

2. In a well drilling pipe tong assembly for a string of pipe having threaded connecting joints where the said pipe is supported in a well bore with a pipe coupling spaced above the point of support, a tong gripping the lower supported section of the coupling, said tong including a handle, means to anchor the handle against pull in one direction, oppositely extending arms on said han-

3. A pair of pipe tongs to operate together upon a pipe joint which is disposed in a vertical position such as a pipe supported in a well bore where the action and reaction are opposed to avoid bending the pipe, independent suspending means for each tong so that the tongs are disposed substantially one above the other, the said means for the lower tong including lateral arms so that the upper tong and its suspending means may be disposed in the space thereby provided, means to anchor one tong, and additional means to exert a pull on the other tong directly away from such anchor.
